UNITED STATES PATENT OFFICE.

GEORGE BEAUJARD, JR., OF NEW YORK, N. Y., ASSIGNOR TO MEYER KOULISH CO., INC., OF NEW YORK, N. Y., A CORPORATION OF NEW YORK.

RING.

Application filed November 19, 1927. Serial No. 234,407.

The present invention is concerned with improvements in rings of the character in which a plurality of annular ring sections are rotatably joined together. Rings of this type are primarily intended for displaying various combinations of stones by rotating the sections relatively to each other, or by rotating the sections as a unit on the finger. Rings of this type as previously designed, have been expensive to manufacture, and have involved soldering operations or complicated constructions which render them unsuitable for embodiment in a low priced article. Most of them furthermore, have not been of attractive appearance, and have been built up of a number of parts which render their assembly complicated and awkward.

In accordance with the present invention, I have provided a ring in which there are no parts except the individual annular ring sections to be rotatably united, in which soldering and other complicated or awkward manufacturing processes are eliminated, and one ring section joined to an adjacent one by the simple expedient of spinning a flange into a groove.

The completed ring is of neat attractive appearance, devoid of projections on its outer and inner surfaces, rugged and durable in construction, and well suited to the requirements of economical manufacture.

With the above noted and other objects in view, the invention consists in certain novel features of construction and combinations and arrangements of parts, as will be more fully hereinafter set forth and pointed out in the claim. The invention may be more fully understood from the following description in connection with the accompanying drawings, wherein—

Fig. 1 is a sectional view showing the two annular sections which are used in making the ring before their assembly.

Fig. 2 is a similar view showing the ring sections assembled.

Fig. 3 is a side elevational view of Fig. 2.

In the drawings I have used the reference numerals 10 and 11 to designate two annular ring sections adapted to be secured together in edge to edge abutting relationship, in such a manner that they are free for relative rota-

tion but locked against relative separation. The numerals 12 and 13 have been used to designate the proposed abutting surfaces of the sections 10 and 11.

Section 10 is provided with a substantially V-shaped groove 14 in its interior; this groove communicating with an annular cut-away portion 15 intersecting the abutment surface 12. Projecting from the surface 13 of the section 11 is a flange 16 of suitable cross sectional shape to fit within the groove 14. This flange as best seen in Fig. 1 normally clears the cutaway portion 15 as the two sections are moved together into abutting relationship.

After the sections are brought together, the flange is spun or worked into the groove by the use of a spinning tool or other appropriate instrumentality in such a manner that the inner surfaces of the two ring sections lie flush with each other with no internal projecting parts. The flange and groove prevent relative separation of the sections and permit relative rotation thereof.

The sections may be provided with openings such as 17 therein, or otherwise suitably treated for the reception of stones indicated in dotted lines at 18.

It will be obvious, that as many sections as desired may be joined together by the means described above; although in most cases, two sections are enough to produce an attractive ring with four possible stone combinations, assuming that each ring section is set with two semi-annular sets of gems.

Obviously, various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claim.

I claim:

A ring including at least two relatively rotatable annular ring sections secured together in edge to edge abutting relationship, one ring section having an internal annular groove therein, the other section having an integral annular extension constituting a

flange fitting the groove and cooperating therewith to lock the sections against separation and permit relative rotation of the sections, the groove being of general V-shape in 5 cross section and communicating with the abutment face of the grooved section, the flange being of material capable of being spun

into the groove and projecting from the abutment surface of the flanged section.

Signed at New York, in the county of New 10 York and State of New York, this seventeenth day of November A. D. 1927.

GEORGE BEAUJARD, JR.
